UNITED STATES PATENT OFFICE.

WHITNEY A. ARCHIBALD, OF BELLINGHAM, WASHINGTON.

LOG-LOADING JACK.

Application filed March 23, 1922. Serial No. 546,000.

To all whom it may concern:

Be it known that I, WHITNEY A. ARCHIBALD, a citizen of the United States, and a resident of Bellingham, in the county of 5 Whatcom and State of Washington, have invented a new and useful Log-Loading Jack, of which the following is a specification.

My invention relates to improvements in log loading jacks, the kind which are 10 mounted on a guy cable of a spar tree over the car to be loaded, and one of the objects of my improvements is to provide a loading jack which will not injure the cable on which it is mounted. Another object of my 15 improvements is to provide a loading jack which will automatically clamp itself fast to the cable on which it is mounted by the weight of the loads which it must bear. Another object of my improvements is to provide a loading jack which can be unclamped 20 from its cable by one while on the ground; and a further object of my improvements is to provide a loading jack which can be readily set in another position on the same 25 cable or moved to another cable.

I attain these objects by the mechanism illustrated in the sheet of drawings accompanying this specification of which it forms a part, and in which Figure 1 is a side elevation of my loading jack, and Fig. 2 is 30 an end elevation of Fig. 1.

Similar characters refer to similar parts throughout. Certain parts are broken away to show other parts hidden thereby.

More particularly: Two similar side plates 3, 3 are clamped together by bolt 4, two bolts 5 and four bolts 6. Clamp block 7 is housed in channel bar 8 which, together with said block is fastened between the upper 40 edges of plates 3 by bolts 6 which pass through both said channel and said block. A groove a^7 is provided in the bottom of block 7 for seating the cable on which the jack is to be mounted. A lower clamping block 9 is 45 housed in channel bar 10. Two bolts 11 pass through transverse holes in said channel and block and the bolt ends are mounted in slots 12 in plates 3 in a manner permitting the free movement for a limited distance of block 9 with channel bar 10 toward and from block 7, but not endwise of said block; neither can block 9 move in channel 10. Groove a^9 lengthwise in block 9 is juxtaposed to groove a^7 and bears on the lower 55 side of the cable on which the jack is mounted. Two hinge ears, a^{10} , only one of which is

shown, provide a bearing for hinge pin 13 on which is mounted for oscillation cam bars 14. Said cam bars each has a curved cam channel 15, each eccentric to one of axle 60 bolts 18, 18. Each cam bar 14 has in its outer end a stop screw 16, only one of which is shown, which bears on the back of channel bar 10 to adjust the nearness with which the cam bar may approach the same. Two 65 clamping arms or levers 17, 17 are mounted for oscillation on axle bolts 18, 18 in plates 3, 3. Each of said clamping arms has mounted in a fork on its upper end a roller 19 on pin 20 adapted to roll in groove 15. 70 Each of proximate lugs 21, 21 on the upper ends of arms 17 has a conical hole in which is soldered one end of release cable 22. Cable 22 is pendent from said lugs, is folded at a^{22} and clamped to form said fold by screw 75 bolt clamps 23. The upper ends of cable 22 are crossed causing the cable to pass downward on either side of sheave 24 which is mounted for rotation on tube a^{24} . Tube a^{24} bears on both of plates 3 and is clamped between said plates by bolt 4 therethrough. In 80 the lower end of each of clamping arms 17 is a hole in which is engaged one of shackles 25. With each of said shackles 25 is engaged one of the end links 26 of a chain having 85 two other links 27 between which is bull ring 28. Each of two eyes 29 has a cross shank a^{29} having a longitudinal hole therethrough which is mounted on one of the lower corners of the jack by one of clamping 90 bolts 5.

In operation: One of my loading jacks is mounted on one of the rear guy cables of a spar tree near the yarding donkey by first removing all of bolts 6 and taking out 95 channel bar 8 with clamp block 7, thus permitting the lower clamp block 9 to be brought up beneath the guy cable. With said cable against block 9 block 7 and channel 8 are replaced between plates 3 and bolts 100 6 replaced as before. The guy cables which maintain the spar tree upright are usually inclined with the ground at an angle of 45° or less. Beneath some of these guys a railroad passes and a car is spotted beneath 105 one of said guy cables and on this guy the loading jack is mounted. The logs to be placed on the car are delivered alongside of the same by the yarding donkey.

With the jack mounted on the proper 110 guy, as stated, a loading block having a loading cable riveted therethrough, is fas-

tened to bull ring 28 and said ring is lashed to loop a^{22} with a rope, then a hand line, which has been passed through a lead block fastened to the top of the spar tree, is connected to the uppermost of eyes 29 and with said hand line the jack and loading block are hauled up said guy to a point vertically above said car when said hand line is made fast, retaining the jack in place. Then a man is drawn up to the jack on the loading cable and he unfastens the rope which fastens ring 28 to loop a^{22} , thus allowing the weight of said loading block to all bear on the lower ends of arms 17 which causes said arms to force rollers 19 apart and along cam channels 15 thus forcing channel bar 10 and block 9 upward to bear on the guy cable, clamping the same between blocks 7 and 9. The man is returned to the car and the loading cable is fastened to a log and the same is lifted with power applied to said cable by the donkey drum around which it is wound. The weight of the log is sufficient to clamp the jack securely to the guy cable and said hand line can be unfastened from the jack, and the loading of logs into cars spotted beneath said jack may continue till it is more convenient to load the logs from near another guy cable. Then the jack is removed by first hitching to it the said hand line and making the same fast. Then a man is hauled up to the jack and fastens the end of a cable from one of the donkey drums to loop a^{22} , and the donkey applies force to said cable causing rollers 19 to approach each other and unclamp block 9. The man then lashes loop a^{22} and ring 28 together with a rope and the weight of the loading block on cable 22 causes the cable clamp to remain free from the guy cable. The hand line is used to lower jack, block and man to the ground down the guy. Once on the ground the jack is released from the guy by removing bolts 6 and block and channel 7 and 8 as before. Then said jack is removed from said guy cable and taken to that guy cable under which it is preferred to have the cars spotted for the further loading of logs thereon. Then the jack is mounted in place on the guy cable as before.

I prefer to use hard wood for clamp blocks 7 and 9. This will not injure the guy cables.

When desired, the eccentricity of cam channels 15 can be changed relative to axles 18 by adjusting with screws 16.

The usual loading jack is a two-wheeled carriage. It has been found that the guy cables are caused to be weakened by crystallization due to the great pressures localized on them by contact with said wheels.

Having thus disclosed my invention, what I claim is new and desire to secure by Letters Patent is,—

1. In a log loading jack in combination, 65 a jack housing, a cable-clamp member fixed

to said housing, a cable-clamp member slidably engaged with said housing adapted to coact with said fixed-clamp member to clamp on a cable between them, and a pair of levers fulcrumed in said housing one end of each of which bears on said movable clamp member adapted to force it into closer proximity to said fixed clamp member when turned on its fulcrum in one direction and the other end of each of which is connectible to a log 70 the weight of which turns said one end in said one direction.

2. In a log loading jack in combination, a jack housing, a cable-clamp member fixed to said housing, a cable-clamp member slidably engaged with said housing adapted to coact with said fixed clamp member to clamp on a cable between them, a cam-channel member adjustably connected to said slidable clamp member, means adapted to vary the distance between said cam-channel member and said slidable clamp member, and a pair of levers fulcrumed in said housing one end of each of which bears on said cam-channel member adapted to force said slidable clamp 80 member into closer proximity to said fixed clamp member when turned on its fulcrum in one direction and the other end of each of which is connectible to a log the weight of which turns said one end in said one direction.

3. In a log loading jack in combination, a jack housing, a cable-clamp member fixed to said housing, a cable-clamp member slidably engaged with said housing adapted to coact with said fixed clamp member to clamp on a cable between them, and a pair of levers fulcrumed in said housing on one end of each of which is mounted a roller for revolution adapted to bear on said slidable 100 clamp member to force it into closer proximity to said fixed clamp member when said one end is turned on its fulcrum in one direction and the other end of each of which is connectible to a log the weight of which turns said one end in said one direction.

4. In a log loading jack in combination, a jack housing, a cable-clamp member fixed to said housing, a cable-clamp member slidably engaged with said housing adapted to coact with said fixed clamp member to clamp on a cable between them, a cam-channel member adjustably connected to said slidable clamp member, means adapted to vary the distance between said cam-channel member and said slidable clamp member, and a pair of levers fulcrumed in said housing on one end of each of which is mounted a roller for revolution adapted to roll in the channel of said cam-channel member and force said slidable 120 clamp member in closer proximity to said fixed clamp member when said one end is turned on its fulcrum in one direction and the other end of each of which is connectible to a log the weight of which turns said one 125 direction.

end of each of said levers in said one direction.

5. In a log loading jack in combination, a jack housing, a cable-clamp member fixed to 5 said housing, a cable-clamp member slidably engaged with said housing adapted to coact with said fixed clamp member to clamp on a cable between them, a pair of levers fulcrumed in said housing one end of each of 10 which bears on said slidable clamp member adapted to force it into closer proximity to said fixed clamp member when turned on its fulcrum in one direction and the other end of each of which is connectible to a log the 15 weight of which turns said one end in said one direction, and a tension member fastened to said one end of each of said fulcrumed levers adapted for connection to power means whereby said one end of each of said 20 levers is revolved in the other direction.

6. In a log loading jack in combination, a jack housing, a cable-clamp member fixed to said housing, a cable-clamp member slidably

engaged with said housing adapted to coact with said fixed clamp member to clamp on a 25 cable between them, a cam-channel member adjustably connected to said slidable clamp member, means adapted to vary the distance between said cam-channel member and said slidable clamp member, a pair of levers fulcrumed in said housing on one end of each of which is mounted a roller for revolution adapted to roll in the channel of said cam-channel member and force said slidable clamp member in closer proximity to said 30 fixed clamp member when said one end of each of said levers is turned on its fulcrum in one direction and the other end of which is connectible to a log the weight of which turns said one end of each of said levers in 35 said one direction, and a tension member fastened to said one end of each of said levers adapted for connection to power means whereby said one end of each of said levers is revolved in the other direction.

WHITNEY A. ARCHIBALD.
